15 Claims. (Cl. 112—125)

The present invention relates to mechanism for controlling the cutting knife of a sewing machine or the like reciprocating operating member driven from a continuously rotating drive shaft through a motion-transmitting system or linkage adapted to convert the rotary motion of said shaft into reciprocating motion of said knife or other driven member.

An important object of the invention is the provision of an improved control mechanism of this type for starting and stopping the operation of the cutting knife or other driven member safely and smoothly without interruption of the rotation and independently of the speed of the driving shaft or member.

While in the following the invention will be described with specific reference to the operation of the material cutting knife of a sewing machine for the trimming or cutting of the work or sewing material during the operation of the machine, it will become apparent that the improved control and operating device shown and disclosed herein may be employed with equal advantage in connection with the operation of other reciprocating devices driven from a continuously operating drive shaft or member.

In its specific embodiment, the invention relates to a material cutting or trimming device for sewing machines comprising a reciprocating cutting knife bar or carrier driven by the arm or drive shaft of the machine through a knuckle joint linkage, wherein in order to stop the operation of and to retract the cutting knife from its operative position to its inoperative position the knuckle joint is operated manually by means of a control lever or the like to a position in which the joint axis coincides with the fixed axis of an oscillating driving lever operatively connected to the drive shaft, on the one hand, and being rotatively connected to one of the component arms or links of said joint. As a consequence, the oscillating movement imparted by said lever to said joint and, in turn, to the knife or other driven member may be reduced to zero smoothly and without interruption of the rotation of the driving shaft, in such a manner as to enable the stoppage of the knife operation instantly and expeditiously, while at the same time retracting the knife from its operative position to an inoperative position spaced from the work or sewing material being operated on by the machine.

According to a known arrangement of this type, the knuckle joint provided in the motion-transmitting path between the driving member and the cutting knife holder or carrier forms a linkage system which has a pair of rotary or pivot axes, one of said axes being adjustable by means of a common control lever for the operation of said knife between an operative and inoperative position and the other of said axes being adjustable for varying the operating stroke of said knife. Inasmuch as such a device has no stationary or fixed axis about which the system is allowed to oscillate, it inherently lacks both

2

the stability and guidance required to ensure a safe and reliable cutting knife control in connection with high speed sewing and the like machines. The prior art arrangement has the further drawback that the adjustment of the cutting knife is subject to misalignment during use due to spring and other variable or yielding forces or adjustments inherent in the prior devices.

According to another arrangement known heretofore and utilizing a knuckle joint linkage as a motion transmitting means, the latter is adjusted between an operative and an inoperative position in its stretched or fully extended position by means of a manually operable control lever. In order to hold the knuckle joint in the extended position, a spring-loaded bolt is provided at the knuckle point near the end of one of the component arms or links, said bolt being urged into a recess in the opposite end of the cooperating arm or link of the joint. Buckling or angular adjustment of the joint is effected by means of a claw or the like having a handle and engaging the bolt rotatably coupling the component joint arms or links.

These and similar arrangements require the provision of a multiplicity of springs, stops and the like parts or elements, whereby to render it impossible to maintain an accurate adjustment or alignment of the motion-transmitting elements such as to ensure a safe and reliable cutting knife control, especially in the case of fast running sewing and the like machines.

Accordingly, among the further objects of the present invention is the provision of a cutting knife or the like control mechanism of the general type referred to for use in connection sewing and the like machines which is both simple in design and efficient in operation; which substantially consists of rigid component parts or elements, to ensure stability of both adjustment and operation; which requires a minimum of operating parts or elements; which will enable a control of the cutting knife or equivalent reciprocating member instantly and expeditiously; which will enable starting and stopping of the cutting knife simultaneously with its operation to and retraction from the operative or cutting position, respectively, by the aid of a single control or operating step; and which can be operated safely and reliably in connection with high speed sewing and the like machines or operating devices.

The invention, both as to its ancillary objects and novel aspects, will be better understood from the following detailed description taken in conjunction with the accompanying drawing forming part of this specification and wherein:

FIG. 1 is a partial perspective rear view of a conventional sewing machine embodying an improved material cutting knife control mechanism constructed in accordance with the principles of the invention; and

FIG. 2 is a fractional representation shown on an enlarged scale and in partly "exploded" form, to more clearly illustrate the control device forming part of FIG. 1.

Like reference numerals denote like parts in both views of the drawing.

With the foregoing objects in view, the invention involves generally the provision of motion-transmitting and control mechanism connecting a continuously rotating drive shaft with a reciprocating driven member, such as the arm shaft and cutting knife, respectively, of a sewing machine, said mechanism in its preferred embodiment

comprising essentially a driving lever arm rotatable about a fixed axis and having oscillating motion imparted to it from said shaft through suitable motion transmitting means, such as an eccentric mounted upon said shaft and having an extension or eccentric rod rotatably connected to said arm. There is further provided a linkage mechanism connecting said lever arm with the cutting knife carrier or the like and comprising a first and a second link and a bolt having an eye at one end with one end of each of said links being rotatably mounted upon said bolt, to form a knuckle joint, and with the remaining end of said first link rotatably connected to said oscillating arm and with the remaining end of said second link rotatably connected to said knife or other driven member, to complete the motion-transmitting path between said shaft and said member. The device further comprises a manually operable control lever having a fixed pivot and arranged to slidably engage the eye of said bolt.

According to the invention, the effective length of said driving or oscillating lever is such as to equal the effective length of said first knuckle joint link, whereby an angular adjustment of said control lever will enable the axis of said bolt or joint to be operated between two relative positions of coincidence and non-coincidence, respectively, of the joint axis with the axis of said oscillating lever arm. As a consequence, the operating stroke of the knife carrier or equivalent driven member may be varied between zero and a predetermined value without interruption of the rotation of said driven shaft, while at the same time retracting the knife away from the work in the inoperative or retracted position or position of coincidence of the knuckle joint axis with the axis of said oscillating lever arm. Inasmuch as only relatively rotatable or linkage connections are utilized by the invention connecting or coupling the component elements of the transmitting and control mechanism, that is, substantially free from any yielding parts or devices such as springs etc., there is ensured a maximum of stability of both the adjustment and operation of the motion control and transmission mechanism between said rotary driving shaft and reciprocating driven member.

Referring more particularly to the drawing, the numeral 1 indicates part of the cloth plate and numeral 2 indicates part of the upper arm terminating in the head 3 of a conventional sewing machine. Mounted upon the arm or drive shaft 4, FIG. 2, of the machine is an eccentric 5 serving as a driving means of the material cutting knife to be described presently, said eccentric having in turn mounted thereon a ring 7 from which extends an eccentric rod or arm 6. The latter extends through an opening 8 of the arm 2 into the interior of a housing 9, FIG. 1, which is attached to the rear of the head 3 by the aid of screws 10 or by any other suitable means.

Rotatably connected to the end of the eccentric rod 6 is the arm 11 of an angular lever 13 rotatable about a fixed pivot axis or shaft 12 and having a second lever arm 14 forming a right angle with the arm 11 in the example illustrated. Rotatably connected to the end of lever arm 14 through a pin 15 is a first knuckle joint link or arm 16 which together with a second arm or link 18 and a bolt or pin 17 forms a knuckle joint connection or linkage with one end of each of said links being rotatably mounted upon said bolt in the manner shown and well understood. The free end of the link 18 is, in turn, rotatably connected through a further link connection 23 to the carrier or knife holder 19 which is mounted for reciprocation adjacent to the needle or stitch forming tools of the sewing machine. In the example shown, the carrier 19 is guided in the vertical direction by a pair of bolts or guide rods 20 and 21 being attached to the head 3, the former slidably passing through a bore and the latter passing between the bifurcated ends of said carrier to which is attached the material cutting or trimming knife 22.

Connected to the free end of the knuckle joint bolt or pin 17 in a direction transverse thereto is a guide sleeve 24,

to form an eye bolt 25 or guideways at right angle to said bolt, through which is passed a cylindrical arm or guide bolt 26. The latter is pivotally mounted at one end by being fixedly connected to a shaft 27 rotatable about a stationary axis parallel to the axis 12 of the oscillating lever 13. Control shaft 27 protrudes outwardly from the housing 9 and carries a locking member or disc 28 being rigidly secured thereto in any suitable manner. Disc 28 is provided with an arcuate slot 31 which is engaged by an actuating pin or rod 32 secured to a control member or cam disc 33 being freely rotatably mounted upon the outer end of the shaft 27 in a position parallel to the locking disc 28. The circumference of member 33 is formed with a camming surface 34 which is engaged by a spring-loaded control rod 35 rigidly secured to and extending transversely from a pawl 37 rotatable about a fixed axis 36 and having a nose 38 adapted to engage either of a pair of notches or depressions 29 and 30 in the member 28. A flat spring 39 resting with one end against a fixed abutment or pin 40 serves to resiliently urge the rod 35 against the cam surface 34 of the control member 33. The actuating rod 32 engaging the slot 31 to form a lost motion connection with the member 28 has its outer end 41 protruding beyond the member 33 rotatably connected to an intermediate lever arm 42 which is in turn rotatably connected at 45 to a control arm or lever 44 rotatable about a fixed shaft or axis 43 and carrying a control knob or the like as shown in FIG. 1.

In operating the cutting device described hereinbefore, the free end of the control lever 44 is operated in an upward or clockwise direction, whereby to cause the actuating rod 32 to rotate member 33 in the same direction about the shaft 27. As a result of the shape of the cam 34, the rod 35 being attached to the pawl 37 and resiliently engaging said cam will be operated to a position wherein the nose 38 of the pawl 37 is released from the notch 30 of the member 28. As a consequence, control shaft 27 is now free to rotate. During this initial operation of the control lever 44, the actuating rod 32 has been displaced to a position such as to abut against the lower inner end of the slot 31 in the member 28.

As the rotation of the control lever 44 is continued, member 28 will be rotated by following the movement 45 of the actuating rod 32, whereby to rotate the control shaft 27 connected to the member 28 in a clockwise direction. After member 28 has reached a position where the notch 29 is opposite to the nose 38 of the pawl 37, spring 39 causes the pawl to again lock the member 28 50 as a result of the shape of the cam surface 34 of the member 33. As a consequence, the control shaft 27 will again be locked as at the beginning of the control operation.

During the rotation of the shaft 27 through an angular 55 distance determined by the distance of the notches 29 and 30 of the member 28, a similar rotation or deflection has been imparted to the guide bolt 26, in such a manner as to cause operation of the axis of the bolt 17 of the knuckle joint from its operative position shown in the drawing to an inoperative position with the axis of the joint or bolt 17 coinciding with the axis 12 of the oscillating lever 13. In this position, no movement is transmitted to the knuckle joint by the eccentric 5 or oscillating lever 13, thus effecting a stoppage of the operation 60 of the knife 22, while at the same time raising the knife through its carrier 22 to an inoperative position spaced from the work being operated on by the stitching tools of the sewing machine.

The same operation takes place in a reverse order by 70 moving the control arm in a downward or counterclockwise direction, as a result of the shape of the camming surface 34, in order to return the device to operative position, substantially without interruption of the rotation of the driving shaft 4, in a manner readily understood from the foregoing.

In the foregoing the invention has been described with reference to a specific operative device. It will be evident, however, that variations and modifications, as well as the substitution of equivalent parts or elements for those shown herein for illustration, may be made in accordance with the broader purview and spirit of the invention as set forth in the appended claims. The specification and drawing are accordingly to be regarded in an illustrative rather than in a restrictive sense.

We claim:

1. The combination with a sewing machine having a rotating drive shaft, a reciprocating carrier and a material cutting knife attached to said carrier, operating mechanism for said knife comprising a lever arm having a fixed pivot axis, motion-transmitting means between said shaft and said arm to oscillate said arm about said axis, linkage means connecting said arm with said carrier comprising a first and a second link and a bolt with means to provide a guideway at a right angle thereto, one end of each of said links being rotatably mounted upon said bolt, to form a knuckle joint, means rotatably connecting the remaining end of said first link to the end of said arm, further means rotatably connecting the remaining end of said second link to said carrier, the effective length of said first link being equal to the effective length of said arm, a control lever having a fixed control shaft and slidably engaging said guideway, and means to operate said control lever between two relative positions of coincidence and non-coincidence, respectively, of said first pivot axis and the axis of said joint.

2. In a sewing machine as claimed in claim 1, said motion-transmitting means comprising a further lever arm rigid with said first arm, an eccentric mounted upon said shaft and having an eccentric rod and means rotatably connecting the end of said rod to said further lever arm.

3. In a sewing machine as claimed in claim 1, said motion-transmitting means comprising a further lever arm rigid with and forming an angle with said first arm, and an eccentric mounted upon said shaft and having an eccentric rod rotatably connected to said further lever arm.

4. In a sewing machine as claimed in claim 1, said last means being comprised of a locking member connected to said control shaft and having a pair of spaced notches, a spring-loaded stationary pawl adapted to engage said notches, to lock said control shaft against rotation, and manually operable control means coupled with said member through a lost motion connection to initially release said pawl from said member and to afford operation of said member between two angular adjusting positions with said pawl engaging either of said notches, respectively.

5. The combination with a sewing machine having a rotating drive shaft, a reciprocating carrier, a material cutting knife attached to said carrier, operating mechanism for said knife comprising a lever arm having a fixed pivot axis, motion-transmitting means between said shaft and said arm to oscillate said arm about said axis, linkage means connecting said arm with said carrier comprising a first and a second link, a bolt, a sleeve transverse to and connected to one end of said bolt, one end of each of said links being rotatably mounted upon said bolt, to form a knuckle joint, means rotatably connecting the remaining end of said first link to the free end of said arm, further means rotatably connecting the remaining end of said second link to said carrier, the effective length of said first link being equal to the effective length of said lever arm, a rotatable control shaft having a fixed axis parallel to said pivot axis, an arm extending transversely from said control shaft and slidably engaging said sleeve, for displacing the axis of said joint between a position of coincidence and a position of non-coincidence, respectively, with said first pivot axis by operation of said control shaft.

6. In a sewing machine as claimed in claim 5, said motion-transmitting means comprising a further lever arm rigid with said first arm, an eccentric mounted upon said shaft and having an eccentric rod, and means rotatably

connecting the end of said rod to the end of said further lever arm.

7. In a sewing machine as claimed in claim 5, said motion-transmitting means comprising a further lever arm rigid with and forming a right angle with said first arm, and an eccentric mounted upon said shaft and having an eccentric rod rotatably connected to said first lever arm.

8. In a sewing machine as claimed in claim 5, said last means being comprised of a locking member connected to

10 said control shaft and having a pair of notches spaced from one another, a spring-loaded stationary pawl adapted to engage said notches, to lock said control shaft against rotation, and manually operable control means coupled with said member through a lost motion connection, to initially release said pawl from said notches, whereby to afford operation of said member between two angular adjusting positions with said pawl engaging either of said notches, respectively.

9. In combination with a rotating drive shaft and a re-

20 ciprocating driven member, operating mechanism comprising a lever arm having a fixed pivot axis, motion-transmitting means between said shaft and said arm to oscillate said arm about said axis, linkage means between said arm and said member comprising a first and a second link and

25 a bolt with means to provide a guideway at a right angle thereto, one end of each of said links being rotatably mounted upon said bolt, to form a knuckle joint, means rotatably connecting the remaining end of said first link to said arm, further means rotatably connecting the remain-

30 ing end of said second link to said member, the effective length of said first link being equal to the effective length of said arm, a rotatable control shaft parallel to said first pivot axis, and an arm extending transversely from said control shaft and slidably engaging the guideway of said bolt.

10. In a device as claimed in claim 9, said motion-transmitting means being comprised of a further lever arm rigid with said first arm, and an eccentric mounted upon said shaft and having an eccentric rod rotatably connected to the end of said further lever arm.

11. In a device as claimed in claim 9, said motion-transmitting means being comprised of a further lever arm rigid and forming a right angle with said first lever arm, and an eccentric mounted upon said shaft and having an eccentric rod rotatably connected to said further lever arm.

12. In a device as claimed in claim 9, including adjusting means comprising a locking member connected to said control shaft and having a pair of notches spaced from one another, a spring-loaded stationary pawl adapted to engage said notches, to lock said control shaft against rotation, and manually operable control means coupled with said locking member through a lost motion connection, further means operably connecting said last means with said pawl to initially release said pawl from said member and to afford rotation of said control shaft between two angular adjusting positions with said pawl engaging either of said notches, respectively.

13. In a device as claimed in claim 12, said notches being spaced and positioned upon said member to define two relative adjusting positions of coincidence and non-coincidence, respectively, of the axis of said joint with said first pivot axis.

14. In combination with a rotating drive shaft and a reciprocating driven member, operating mechanism comprising a lever arm having a first fixed pivot axis, motion-transmitting means between said shaft and said arm to oscillate said arm about said axis, linkage means connecting said arm with said member comprising a first and a second link and a bolt, one end of each of said links being rotatably mounted upon said bolt, to form a knuckle joint, means rotatably connecting the remaining end of said first link to the end of said arm, further means rotatably connecting the remaining end of said second link

70 to said member, the length of said arm being substan-
